DEHORNING DEVICE

Hal C. Hunter, Denver County, James A. King, Arapahoe County, and Marion E. Moffitt, Adams County, Colo., assignors to Standard Precision Electronics, Inc., Denver, Colo., a corporation of Colorado

Filed Sept. 13, 1968, Ser. No. 13,533

Term of patent 14 years

Int. Cl. D30—99
U.S. Cl. D30—99

FIGURE 1 is a perspective view of a dehorning device showing our new design;

FIGURE 2 is a top plan view of the dehorning device shown in FIGURE 3;

FIGURE 3 is a rear elevational view of the dehorning device shown in FIGURE 1;

FIGURE 4 is a bottom plan view of the dehorning device shown in FIGURE 3;

FIGURE 5 is a left end elevational view of the dehorning device shown in FIGURE 3; and

FIGURE 6 is a right end elevational view of the dehorning device shown in FIGURE 3.

We claim:

The ornamental design for a dehorning device, as shown.
